UNITED STATES PATENT OFFICE.

POWELL EVANS, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

DIFFERENTIAL DRY-PIPE VALVE.

1,418,140.

Specification of Letters Patent. Patented May 30, 1922.

Application filed November 7, 1919. Serial No. 336,462.

To all whom it may concern:

Be it known that I, POWELL EVANS, a citizen of the United States, residing in Philadelphia, Pennsylvania, have invented 5 5 Differential Dry-Pipe Valves, of which the following is a specification.

One object of this invention is to provide means for insuring, assisting and accelerating the operation of the dry pipe valve of 10 an automatic fire extinguishing system upon the opening of one or more of the sprinkler heads of such system;—the invention more particularly contemplating a novel device for causing air under pressure to act on the 15 under side of the air clapper in such manner as to lessen the time required for the operation of the dry pipe valve and thus hasten the delivery of water to the open sprinkler head.

20 Another object of the invention is to provide an automatic device for delivering air under pressure to the atmospheric chamber of a dry pipe valve for the purpose of accelerating the opening of the air valve when 25 the pressure of the air in the system to which the device is connected shall have fallen to a predetermined point.

It is also desired to provide a dry pipe valve of the differential type whose parts 30 shall be of such arrangement and design as to permit of a material reduction in the dimensions of the device for a given capacity;—the invention more especially contemplating a novel construction and arrangement of the air and water clappers whereby it is possible to mount these in cooperative positions within a relatively small and compact casing structure.

I further desire to provide a dry pipe 40 valve with a novel form of air clapper particularly designed to fit over and enclose a water clapper, the whole being assembled with a view to making it possible for air at a definite pressure acting on the air clapper to normally maintain the water clapper closed against the higher pressure acting thereon.

These objects and other advantageous 50 ends I attain as hereinafter set forth, reference being had to the accompanying drawings, in which,

Fig. 1 is a vertical section of a dry pipe valve equipped with my invention;

Fig. 2 is a vertical section illustrating an arrangement and construction of water and air clappers different from that of Fig. 1;

Fig. 3 is a horizontal section on the line 3—3, Fig. 2, and

Fig. 4 is a perspective view of the drip valve shown in Figs. 2 and 3.

In Fig. 1 of the above drawings, 1 represents the main casing of a dry pipe valve having a bottom opening or inlet 2 designed for connection to a water supply system and having a top opening or outlet 3 designed for connection to a sprinkler system. This casing is divided into two chambers by an inclined partition in which is formed a circular opening whose central point lies in the center line with the two 65 openings 2 and 3.

The opening 2 has a seat 4 for the reception of a water valve or clapper 5, which is connected to an arm 6 rotatably mounted on a pivot pin or bar 7 so as to be free to swing 75 with the valve 5 into the position shown in dotted lines, to one side of the line of the openings 2 and 3;—the connection between said arm and valve being such as to permit of a slight relative movement for the purpose of insuring proper seating of said valve.

The opening 8 through the partition is provided with a circular seat 9 for coaction with an air valve or clapper 10 mounted to swing in the chamber 20 upon a pivot pin 85 or bar 11 and having a projection 12 from its under face designed to engage the arm 6 in such manner as to hold the clapper 5 closed as long as said air valve is closed. The latter also has mounted on its lower face a 90 flexible seat-engaging ring 13 for insuring a tight joint with the seat 9 and so formed and attached that it has a substantially frusto-conical form when not engaging said seat.

Said air valve or clapper 10 is formed with a segmental, rearwardly projecting extension 14 substantially concentric with its pivot pin 11 and formed with a series of ratchet teeth 15 designed to coact with a 100 pawl 16 pivotally hung from a pin 17 supported by a pair of lugs 18. The latter are

- preferably formed as part of and project inwardly from a cover plate 19 designed to normally close the air chamber 20 of the dry pipe valve and said pawl is so carried that 5 its lower or toothed end tends at all times to swing toward the segment 14 of the air clapper so as to engage the teeth thereof and retain the clapper in any position to which it may rise from its seat.
- 10 The upper end 21 of the pawl is extended into position to coact with a stop 22 placed on the cover plate 19 to limit the swing of the main or lower portion of the pawl and thereby insure its occupying a position to 15 coact with the segment when the cover plate is applied.

In accordance with one feature of my invention, I mount on or adjacent the dry pipe valve a two-part casing 23 and 24 and 20 clamp between its parts a flexible diaphragm 25. This casing is so mounted that the part 23 is above the part 24 and the latter has two pipes 26 and 27 of which the first is connected to the air chamber 20 of the dry pipe 25 valve, while the second is connected to the atmospheric chamber 28 thereof which has a small valve seat 29 leading to a drain and constituting a normally open trap controlled by a valve 30 hung from one arm of a lever 31 fulcrumed on the pivot pin 7 and having its other arm engaged by the arm 6 of the water clapper.

The arrangement is such that the trap valve 30 is held open as long as the water clapper 5 is closed, although by reason of its weight, it will automatically close as soon as said clapper opens and allows the arm 6 to swing upwardly on its pivot pin 7.

The diaphragm 25 has formed through it 40 a small opening 36, which if desired, may be closed by a check valve 37 so placed as to permit flow from the chamber 24 into the chamber 23 while preventing a return flow. While the opening of the pipe 26 to the chamber 24 of the accelerator casing is unrestricted, this latter is so formed adjacent the opening to the pipe 27 as to provide a 45 passage 35 having a valve seat 41 and a co-operating valve 39 supported by a stirrup 38 carried by or connected to the diaphragm 25. This valve 39 is at all times urged toward its seat 41 by a spring 40 and normally holds the diaphragm 25 in its uppermost position.

55 With the above described arrangement of parts, under conditions of operation the water under pressure in the supply system acts through the opening 2 against the water clapper 5, which however is normally maintained closed by reason of the air pressure in the sprinkler system acting in the chamber 20 against the air clapper 10. The trap valve 30 is thus maintained in its open position so that atmospheric pressure exists in the 60 chamber 28. The air under pressure in the

sprinkler system fills the chamber 24 of the accelerator casing and passing through the opening 36 in the diaphragm 25 also fills the chamber 23 thereof. Since however the pipe 27 and passage 35 contain air at atmospheric 70 pressure, the spring 40 insures that the valve 39 is closed.

If now an automatic sprinkler opens at some point of the system connected to the pipe 50, there is a resulting reduction of the 75 air pressure in the chamber 20 of the dry pipe valve, and when this pressure reaches a predetermined low point, the water pressure in the inlet 2 causes unseating of the air clapper 10 and the release and opening 80 of the water clapper 5. By means of the accelerator device above described however, before the pressure in the chamber 20 has fallen sufficiently far to permit unseating of the air clapper, it is sufficiently reduced in 85 the chamber 24 to allow the air in the chamber 23 to force downwardly the diaphragm 25, the valve 37 being closed or the opening through the diaphragm being relatively restricted. The accelerator valve 39 is there- 90 upon opened so that the air under reduced pressure from the chamber 20 and from the sprinkler system is delivered through the passage 35 and pipe 27 to the atmospheric chamber 28 of the dry pipe valve. 95

Even if the water clapper 5 has not opened sufficiently far to allow closing of the trap valve 30, this air under pressure acting on the relatively large area of the under face of the air clapper 10, exerts a force tending 100 to unseat said clapper and thus materially assists the water clapper, causing opening both of the air clapper and of said water clapper in a shorter time after the opening of an automatic sprinkler head in the sys- 105 tem, than would be the case if the opening of the air clapper was unassisted. The delivery of water to the open sprinkler head is thus insured in a shorter time after the beginning of the fire which caused such head 110 to open, and there is a considerably increased probability of extinguishing the fire before it has attained great headway than would ordinarily be the case in the absence of my invention. 115

If desired the dry pipe valve may be constructed as shown in Figs. 2 and 3, with a cylindrical extension 4^a constituting a seat for a water clapper 5^a mounted on an arm 6^a pivoted on or rotatable with a hinge or pivot 120 pin 7^a extending across the casing. The seat sleeve 4^a is threaded into the sides of the inlet passage or opening 2 and is outwardly flanged to clamp in place a metal ring 53 carrying an outwardly projecting, flexible, 125 substantially frusto-conical seat element 9^a, designed to cooperate with the annular face of the air clapper 10^a. This latter is mounted upon a second pivot pin or shaft 11^a ex- 130 tends across the casing 1^a parallel with

the pin or shaft 7^a of the water valve and on the opposite side of the seat sleeve 4^a therefrom.

It is noted that the flexible seat ring 9^a for the air clapper 10^a projects at a level below the top of the seat sleeve 4^a and is eccentric thereto, its center line being displaced toward the pivot of the water clapper 5^a in order that the air clapper 10^a, which is 10 upwardly dished or concave so as to receive within it said water clapper, may clear the latter under operating conditions. Within the hollow of the air clapper is mounted a bearing plate 12^a designed to engage the 15 arm 6^a of the water clapper so as to hold the latter closed as long as a ring 13^a on the face of the air clapper remains in engagement with its seat 9^a.

In order to insure that the air clapper shall remain open after it has been raised a predetermined distance from its seat, I provide it with a toothed segment 14^a as before and pivotally mount a weighted pawl or tooth 16^a on a pin 17^a carried by a plug 52. 20 This is threaded into a suitably formed opening in the casing 1^a in such position that the pawl at all times tends to swing toward and remain in engagement with the toothed edge of the segment 14^a;—the arrangement 25 being such that the water clapper, after moving out of engagement with its flexible seat 9^a, is retained in its raised or open position. As before the chamber between the two valves 10^a and 5^a is normally open to 30 the atmosphere through a drain passage 54 terminating in a valve seat 29^a, and a valve 30^b is so hung on a level 30^b carried by the pivot spindle 7^a as to be held open as long as the water valve is closed and permitted 35 to close when said latter valve is open.

With the above described arrangement of parts, the pipe 27 leading from the accelerator (which being of the construction shown in Fig. 1, is omitted from Figs. 2 and 3) 40 communicates with the atmospheric chamber between the air and water clappers through an opening suitably placed in the ring 53 and the pipe 26 as before, enters the air chamber 20^a. Under normal conditions 45 the pressure of the air in the sprinkler system, acting in the chamber 20^a of the valve casing, holds the air clapper 10^a to its yielding seat 9^a, and through the plate 12^a, holds the water clapper 5^a upon its seat sleeve 4^a 50 against the relatively higher water pressure exerted through the inlet 2. When however there is a reduction of the air pressure in the chamber 20^a such as would be caused by the opening of a sprinkler head in the system connected thereto, the air clapper 10^a is forced from its seat, partly by the pressure of the water acting through the clapper 5^a and arm 6^a and partly by the air under 55 pressure delivered to the space 18^a between the clappers by the accelerator through the 60 65

pipe 27, so that said air clapper swings up and to one side of the line of the inlet 2 and outlet 3 into a position in which it is retained by the pawl 16^a engaging a tooth of the segment 14^a. This upward movement 70 of the air clapper permits the water clapper to swing in the opposite direction on its pivot pin 7^a, thus leaving a clear passage for the water to flow from the inlet through the chamber 20^a and into the sprinkler system through the outlet 3. 75

According to one feature of my invention therefore, there is a supply of air under pressure delivered to the atmospheric chamber of the dry pipe valve after the opening 80 of a sprinkler head, with the result that the time elapsing before water flows into and is delivered from the sprinkler system is materially reduced, and it is noted that the cross sectional areas of the conduits connecting the chamber 20 with the accelerator casing 24, as well as that connecting the latter with the atmospheric chamber of the dry pipe valve, are relatively large, particularly 85 as compared with the trap opening, so that the operation of the device is insured even though the trap passage, which is of relatively small cross sectional area, is open.

After the operation of the system, the closure of the water clapper 5 and of the 90 air clapper 10 permits of air under pressure being again delivered from the chamber 20 to the sprinkler system, and the consequent flow of air to the chamber 24 of the accelerator casing, acts on the diaphragm 25 to 95 again allow seating of the valve 39, so that the various parts are in positions for operation.

I claim:

1. An accelerator consisting of a casing 105 having an inlet and an outlet and provided with a closed chamber connected to receive fluid under pressure from the inlet; a normally closed valve between said inlet and outlet; with a member movable under the 110 action of the fluid under pressure in said chamber for opening the valve when the pressure in the inlet falls to a predetermined point.

2. An accelerator consisting of a casing 115 having a movable element dividing it into chambers of which one is provided with an inlet and an outlet; a valve mounted between the inlet and outlet for controlling the latter and operatively connected to said member; and means normally holding said valve closed, the second chamber being normally filled with fluid under pressure for moving the member and opening the valve when a predetermined fall of pressure occurs at the inlet of the casing. 120

3. An accelerator consisting of a casing; a perforated diaphragm dividing said casing into chambers of which one has an inlet and an outlet; a normally closed valve con- 125

5 nected between the inlet and outlet for controlling the latter; with means connecting the valve to the diaphragm and positioned to cause opening of said valve when a pre-
determined unbalanced pressure is exerted on the diaphragm.

- 10 4. An accelerator consisting of a casing; a diaphragm dividing said casing into chambers and having a restricted passage, one of said chambers having an inlet and an outlet; a valve interposed between said inlet and outlet for controlling the latter; and means for mechanically connecting said valve with the diaphragm.
- 15 5. An accelerator consisting of a casing; a diaphragm dividing said casing into chambers connected through a restricted passage, one of said chambers having an inlet and an outlet; a valve interposed between said inlet and outlet for controlling the latter; means for operatively connecting said valve with the diaphragm; and a spring normally holding said valve closed.
- 20 6. The combination in a differential dry pipe valve of a casing having a water inlet and an outlet; a water valve for closing the inlet; with a concave structurally independent air valve fitting over and enclosing the water valve when this is in its closed posi-

30 tion, said latter valve being mounted to open in a direction opposite that taken by the water valve.

35 7. The combination in a differential dry pipe valve of a casing having a water inlet and an outlet; a valve seat for said inlet; a second valve seat extending eccentrically around the first valve seat and in a plane parallel thereto; a water valve mounted to coact with the first valve seat; with a concave structurally independent air valve positioned to engage the second seat and enclose the water valve.

40 8. The combination in a differential dry pipe valve of a casing having a water inlet and an outlet; two valves pivotally mounted on opposite sides of the inlet and formed to fit one inside of the other; with eccentrically disposed seats for said two valves.

45 9. The combination in a differential dry pipe valve of a casing having a water inlet and an outlet; a seat sleeve for the inlet; a valve ring clamped in place by said seat ring; with two valves pivoted on opposite sides of the inlet and formed to fit one inside of the other in positions to respectively coact with the seat sleeve and with the valve ring.

50 In witness whereof I affix my signature.
POWELL EVANS.
